RECEPTACLE FOR STORING AND MIXING
DENTAL PREPARATIONS

Erwin Baumann, Nendeln 108, Liechtenstein, and
Gerhard Beham, Im Lett 798, Vaduz, Liechtenstein

Filed Dec. 19, 1966, Ser. No. 5,083

Term of patent 14 years

(Cl. D9—216)

FIG. 1.

FIG. 2.

FIG. 4.

FIG. 3.

FIG. 1 is a perspective view of a receptacle for storing and mixing dental preparations, showing our new design;

FIG. 2 is an elevational view;

FIG. 3 is a top plan view; and

FIG. 4 is a bottom plan view thereof.

We claim:

The ornamental design for a receptacle for storing and mixing dental preparations, as shown.
